MOBILE STAND FOR THE DISPLAY AND MERCHANDISING OF PACKAGED GOODS AND THE LIKE

Georges Tirlet, Saint-Germain-de-Livet Calvados, France, assignor to Etablissements G. Tirlet, Calvados, France,
a corporation of France

Filed May 15, 1959, Ser. No. 55,914

Claims priority, application France Nov. 18, 1958

Term of patent 14 years

(Cl. D80—10)

FIG. 2.

FIG. 1.

FIG. 4.
FIG. 3.FIG. 1 is a top perspective view of a mobile stand for the display and merchandising of packaged goods and the like showing my new design;

FIG. 2 is a top plan view thereof;

FIG. 3 is a side elevational view thereof;

FIG. 4 is a vertical sectional view thereof taken on line 4-4 of FIG. 3.

I claim:

The ornamental design for a mobile stand for the display and merchandising of packaged goods and the like, substantially as shown.
